UNITED STATES PATENT OFFICE.

FARNUM F. DORSEY, OF ROCHESTER, NEW YORK, ASSIGNOR TO NORTH EAST ELECTRIC COMPANY, OF ROCHESTER, NEW YORK, A CORPORATION OF NEW YORK.

ODOMETER.

1,409,366.

Specification of Letters Patent. Patented Mar. 14, 1922.

Application filed June 8, 1921. Serial No. 476,060.

To all whom it may concern:

Be it known that I, FARNUM F. DORSEY, a citizen of the United States, residing at Rochester, in the county of Monroe and 5 State of New York, have invented certain new and useful Improvements in Odometers; and I do hereby declare the following to be a full, clear, and exact description of the invention, such as will enable others skilled 10 in the art to which it appertains to make and use the same.

This invention relates to odometers or similar registering instruments, in which provision is made for resetting the counting-wheels manually, either to zero or to 15 any required number.

The object of the invention is to produce an odometer in which the construction of the driving and resetting mechanism is 20 simple, compact and conveniently operable.

To the foregoing end the invention consists in the construction and arrangement of the odometer hereinafter described, as it is defined in the appended claim.

25 In the accompanying drawings, Fig. 1 is a front-elevation of odometer mechanism embodying the present invention; Fig. 2 is a right-hand end-view of the same; Fig. 3 is a plan-view of the mechanism, showing 30 parts of the frame and the casing of the instrument in section; and Fig. 4 is a view partly sectional on the line 4—4 in Fig. 2.

The invention is illustrated as embodied in an odometer of a type commonly used on 35 motor-vehicles, the instrument comprising two trains of registering or counting-wheels 5 and 6, of which the wheels 5 give a permanent and complete registration of the distance traveled, while the wheels 6 constitute 40 what is commonly called the trip-train, being arranged to be reset whenever desired by the user.

The counting-wheels are all mounted concentric with a drive shaft 7, which is actuated, 45 through intermediate mechanism, by a worm-wheel 8. The mechanism for driving and for interconnecting the wheels need not be further described, as such mechanisms are well known, and the specific arrangement employed has no connection with the 50 present invention.

The counting-wheels are enclosed in the usual cylindrical casing 9, of which only a small portion is shown, the front of this 55 casing being closed by a glass plate 10, and

a face-plate 11, secured in place by a bezel-ring 12. The mechanism of the instrument is supported by a frame 13, enclosed within the casing but provided with an integral bearing-block 14 which projects outwardly 60 through the side of the casing. This bearing-block is provided with a horizontal opening through which the drive-shaft 7 extends to the outside of the bearing-block, this opening including a slot 15 extending 65 to the front of the block, so that the shaft may be conveniently introduced into the bearing. The bearing-opening is provided with a bearing-sleeve 16 which is of greater diameter than the slot 15, and which serves 70 both to provide a suitable bearing-surface for the shaft and to secure the shaft in position. This arrangement constitutes no part of the present invention.

At its outer end the drive-shaft is provided with a pinion 17 which meshes normally with a gear 18. The gear is fixed on the outer end of a lay-shaft 19, and this lay-shaft is arranged to turn and also to move lengthwise in a second bearing-opening 80 extending through the block 14. On the inner end of the lay-shaft is fixed a pinion 20, which meshes constantly with a wide-face ear 21. This gear is loosely mounted upon the drive-shaft, so that it may turn 85 independently of the shaft.

Fixed to the gear 21 is a drive-plate 22, which has lugs 23 cooperating with suitable recesses on the first wheel of the trip-train 6. Through the connections just described 90 the trip-train is driven by rotation of the gear 21. In the normal operation of the instrument, therefore, as the drive-shaft 7 rotates in accordance with the speed of the vehicle, the trip-train is driven by the operation of the parts 17, 18, 19, 20, 21 and 22. The engagement of the gear 18 with the pinion 17 is normally maintained by a coiled spring 24, which surrounds the lay-shaft 19, and presses it constantly outward, the 95 lengthwise movement of the shaft being limited by engagement of its rounded outer end with the resetting-shaft 25.

The resetting mechanism comprises a shaft 25 arranged at a right angle to the lay-shaft and arranged to turn and slide in a bracket 26 secured to the outer face of the bearing-block 14. This shaft has a conical portion 27 engaging the end of the lay-shaft, and it carries a crown gear 28, which is 100

110

drawn into engagement with the gear 18 when the resetting-shaft is pulled outwardly. The outer end of the shaft is in the form of a knurled head 29, by which it may be conveniently manipulated. A groove 30, turned in the shaft 25, is engaged by a hairpin-spring 31, shown in dotted lines in Fig. 1, this spring being enclosed in a casing 32 mounted on the bracket 26. The spring acts to retain the resetting-shaft in its operative position, with the gears 18 and 28 in mesh. The conical portion 27 forces the lay-shaft inwardly, thus disengaging the gear 18 from the pinion 17. The lay-shaft may then be freely turned by rotation of the resetting-shaft in either direction, and this motion is transmitted to the first of the series of counting-wheels 6. After the resetting operation has been performed the shaft 25 is pushed rearwardly, thus permitting the spring 24 to force the lay-shaft outwardly again so as to engage the gear 18 with the pinion 17, and the normal driving of the mechanism by the drive-shaft 7 is thus resumed.

The invention is not limited to the embodiment thereof hereinbefore described and illustrated in the accompanying drawings, but it may be embodied in various other forms within the scope of the following claim.

The invention claimed is:

An odometer comprising: a frame-member provided with two parallel bearings; a drive-shaft and a lay-shaft mounted in said bearings respectively; a set of counting-wheels concentric with the drive-shaft; a gear connected with the first counting-wheel and freely rotative about the drive-shaft inside said frame-member; a pinion on the inner end of the lay shaft and meshing constantly with said gear; a pinion on the outer end of the drive-shaft; a gear on the outer end of the lay-shaft and meshing normally with the last-mentioned pinion; and means for moving the lay-shaft lengthwise to disengage the last-mentioned gear and pinion and for rotating the lay-shaft to reset the counting-wheels.

FARNUM F. DORSEY.
